VENDING MACHINE

Sam Reisner, Pacific Palisades, Calif., assignor to Osco Corporation, a corporation of California

Filed Oct. 23, 1967, Ser. No. 9,111

Term of patent 14 years

(Cl. D52—3)

FIG. 2.

FIG. 3.

FIG. 4.

FIGURE 1 is a perspective view of a vending machine showing my new design;

FIGURE 2 is a side elevational view thereof illustrating the side not visible in FIGURE 1;

FIGURE 3 is a top plan view thereof; and

FIGURE 4 is a front elevational view thereof.

The rear of the machine appears as a flat planar surface except for the statue portion and the bottom of the machine appears as a flat planar rectangle corresponding to the rectangular outline of the machine shown in the top plan view.

The essential features of the design reside in the full line portions shown in the drawing.

I claim:

The ornamental design for a vending machine, substantially as shown and described.
